UNITED STATES PATENT OFFICE.

EDWARD W. BURGESS, JR., OF MILWAUKEE, WISCONSIN.

STUMP-PULLING ENGINE.

1,261,760.

Specification of Letters Patent.

Patented Apr. 9, 1918.

Application filed February 21, 1914, Serial No. 820,108. Renewed October 29, 1917. Serial No. 199,206.

To all whom it may concern:

Be it known that I, EDWARD W. BURGESS, Jr., a citizen of the United States, residing at Milwaukee, in the county of Milwaukee and State of Wisconsin, have invented certain new and useful Improvements in Stump-Pulling Engines, of which the following is a specification.

My invention relates to hoisting engines 10 in its general adaptation, and in particular to that class designed primarily for use in clearing cut over land, such as pulling and bunching stumps, piling and loading logs, pulling underbrush, and other heavy duty.

15 The object of my invention is to provide a mechanism simple and strong in its construction, conveniently manipulated, and efficient in operation. I attain these objects by means of the mechanism illustrated 20 in the accompanying drawings, in which—

Figure 1 is a top plan view of an engine having my invention embodied in its construction;

Fig. 2 is a side elevation of Fig. 1;

25 Fig. 3 is a vertical cross section of Fig. 1 along line A—B;

Fig. 4 is a cross section of Fig. 1 along line C—D;

30 Fig. 5 is a cross section of Fig. 1 along line E—F;

Fig. 6 is a cross section along line G—H of Fig. 1;

Fig. 7 is an end elevation of Fig. 6;

35 Fig. 8 is a cross section along line I—J of Fig. 1;

Fig. 9 is a vertical cross section of Fig. 8 along line K—L;

Fig. 10 is a detached top plan view of a detail of Fig. 1 designed to illustrate the 40 operation of the motion reversing mechanism connected with the main pulling drum;

Fig. 11 is a vertical cross section of Fig. 10 along line M—O;

Fig. 12 is a side elevation of part of the 45 friction reverse mechanism connected with the main power drum;

Fig. 13 is a cross section of Fig. 1 along line P—Q;

50 Fig. 14 is a broken cross section of Fig. 1 along line R—S;

Fig. 15 is a side elevation of Fig. 14; and

Fig. 16 is a detached fragmentary detail designed to illustrate the operation of the reverse gear mechanism.

55 The same reference characters designate like parts throughout the several views.

The machine is mounted upon a base member 1, comprising a series of longitudinally disposed timber members 2 secured together by transverse bolts 3, and 4 represents strap members secured to opposite sides of the base by means of bolts 5 and having secured to opposite ends thereof eye members 6 whereby the machine may be drawn forward or anchored, as desired. 60 7 represents the fixed base of a turn-table having horizontally disposed flange members 8 upon opposite sides thereof whereby it is secured to the base 1, and a vertically disposed annular flange member 9, and 10 represents the upper member of the turn-table, resting upon balls 11 received by ball races in the two members, and rotatable upon the fixed member, and 12 represents a ring member secured to the flange 9 by means of cap screws 75 13, and projecting outside of the periphery thereof and engaging with a shoulder upon a concentric flange member 13¹ forming part of the upper member, is operative to retain the upper member of the turn-table in co-acting relation with the lower member. The upper member 10 is provided upon opposite sides thereof with parallel flange members 14 whereby it is secured to the lower sides of longitudinally disposed frame plates 15, 80 and 16 represents reinforcing angle members secured to the outside of the plates and to the flange members.

Secured to the lower inner sides of the frame plates 15, upon one end of the turn-table, are angle members 17, upon which is carried an engine sub-base 18, having its opposite sides secured to the frame plates 15 by means of bolts 19; an internal combustion engine, including a base 20, cylinder 21, 90 crank shaft 22, and fly wheels 23, secured to opposite ends of the crank shaft, being mounted upon the sub-base 18. The crank shaft 22 is journaled in two bearings 24 carried by the engine base 20, upon opposite sides of the crank part 25 of the engine crank shaft, and a third adjustable bearing 26 carried by a pillow block 27 secured to the engine sub-base 18, and 28 represents a power transmission pinion secured to the 95 engine crank shaft inside of the bearing 26 and meshing with an intermediate pinion 29 journaled upon a stub shaft secured to the pillow block 27.

Secured to the frame plates 15, upon opposite sides of the machine, are bearing blocks 30, in which is secured a transverse shaft 110

31 disposed parallel with the engine crank shaft and having journaled thereon a gear wheel 32 and a winding drum 33; the gear wheel meshing with the intermediate pinion 29. The gear wheel 32 is provided with angularly disposed clutch rims 34, upon opposite sides thereof, and 35 represents a sleeve member journaled upon the shaft 31, having upon one end a flange 36 that abuts 10 a washer 37 interposed between the flange and the outside end of the hub 38 of the gear wheel 32; the opposite end of the sleeve engaging with the adjacent bearing block 30. Slidably mounted and journaled upon 15 the sleeve 35 is a combined pinion 39 and clutch ring 40, the clutch ring being adapted to operatively engage with the adjacent clutch rim 34 when moved in one direction, and to be disengaged therefrom when moved 20 in an opposite direction; the hub of the clutch ring being provided with a peripheral channel that receives a two-part clutch shipping ring 41 that is connected with the bearing block 30 by means of rods 42, having 25 their axes in a vertical plane and provided with right and left threaded portions at their opposite ends that engage with like threaded openings in the clutch shipping ring and bearing block. The winding drum 33 is provided upon the end adjacent the gear wheel 32 with a clutch ring 43 adapted to operatively engage with the adjacent clutch rim 34 when the drum is moved in one direction, and to be disengaged therefrom when moved 30 in an opposite direction; the drum being rotatably and slidably mounted upon the shaft 31, and 44 represents washers interposed between the inner end of the drum and the adjacent end of the 35 hub of the gear wheel 32. The opposite end of the drum is provided with a channeled brake rim 45 that operatively receives a brake band 46, and an axially extending annular flange member 47 provided with a 40 peripheral channel 48 that receives a two-part clutch shipping ring 49, like in form with the clutch shipping ring 41, and connected in the same manner by means of right and left threaded rods 50 with the adjacent bearing block 30.

50 51 represents a longitudinally disposed shaft having its opposite ends secured in bearing members 52 secured to the lower side of one of the frame plates 15, and having journaled thereon a relatively long sleeve member 53, having a vertically disposed hand lever 54 at one end thereof, and an inwardly extending arm 55 at its opposite end, and 56 represents a transverse shaft 50 having its opposite ends journaled in bearings 57 secured to the frame plates 15, and provided with laterally extending arms 58 at opposite ends thereof adjacent the inner ends of the bearings 57, one of the arms adjacent the shaft 51 being connected with

the arm 55 by means of a link member 59, and the other arm, by means of a link 60, with the lower end of a connecting bar 61 pivotally connected with the outer ends of arms 62 adjustable angularly upon the rods 42, whereby, when the hand lever 54 is turned axially away from the machine, the rods 42 are turned in a direction to cause the clutch ring 40 to engage with the adjacent clutch rim 34 in a manner to cause the combined pinion 39 and clutch ring 40 to rotate with the gear wheel 32; and when the hand lever 54 is moved axially toward the machine 75 the rods 42 are turned in a direction to separate the clutch members. 80

The winding drum 33 is caused to engage and rotate with the gear wheel 32 by means substantially the same as that controlling the movement of members 39 and 40, comprising a sleeve member 63 journaled upon the shaft 51, adjacent the sleeve 53, and having a vertically arranged hand lever 64 secured thereto, and an inwardly extending arm 65 integral with the sleeve and connected, by means of a link 66, with the lower end of a bar 67 that is pivotally connected with one end of arms 68, that have their opposite ends secured to the rods 50 in a manner to be adjustable angularly thereon, whereby, when the hand lever 64 is moved axially away from the machine, the clutch ring 43 of the winding drum 33 is caused to engage with the adjacent clutch rim 34 of the gear wheel 32 in a manner to cause the winding drum to be rotated with the gear wheel and to be released therefrom when moved in an opposite direction. The arms 62 and 68 are split upon one side of the axes of the rods 42 and 50, and are clamped to the rods by means of cap screws 69, that 95 may be released, permitting the rods to be turned in a manner to adjust the relative operative positions of the hand levers and the clutch engaging parts. 70 represents a third sleeve member journaled upon the shaft 51 and having a vertically disposed hand lever 71 secured thereto, and an inwardly extending arm 72 integral therewith that is connected by means of a link 73, with a longitudinally disposed arm 74 integral 100 with a sleeve 75 journaled upon a transverse shaft 76, having its opposite ends journaled in bearing boxes 77, secured to the frame plates 15 upon opposite sides of the machine, and 78 represents other arms spaced apart 105 upon the opposite side of sleeve 75, that are pivotally connected to opposite ends of a brake band 79 by means of pins 80; the band being adapted to operatively engage with the brake rim 45 of the winding drum 33 110 in a common way when the hand lever 71 is moved in one direction, and to be disengaged therefrom when the lever is moved in an opposite direction. 81 represents a fourth sleeve journaled upon the shaft 51 be- 115

120

125

130

yond the sleeves 63 and 70, and provided with an inwardly extending arm 82 that is connected, by means of a link 83, with an arm 84 integral with a sleeve 85 that is secured to the shaft 76 between the adjacent bearing box 77 and the end of sleeve 75, and 86 represents a collar secured to the shaft at the opposite end of the sleeve. 87 represents an arm secured to the opposite end of shaft 76, outside of the adjacent bearing box 77, and connected, by means of a rod 88, with an arm 89 secured to the outside end of a short rock shaft 90 journaled in a bearing block 91 secured to the upper side of one of the frame plates 15, and 92 represents a pawl member secured to the opposite end of the shaft. 93 represents a transverse shaft having its opposite ends secured in box members 94 secured to the frame plates 15 upon opposite sides of the machine, and journaled thereon is a gear wheel 95 that meshes with the pinion 39, the gear wheel being secured to a flange 96 integral with the adjacent end of a sleeve 97 that is journaled upon the shaft 93, and integral with the opposite end of the sleeve is a pinion 98. The gear wheel 95 is provided with internally disposed ratchet teeth 99, which the pawl member 92 is adapted to engage with when the shaft 90 is rocked in one direction. 100 represents a transverse shaft having its opposite ends secured in bearing blocks 101 secured to the frame plates 15 upon opposite sides of the machine, and 35 journaled thereon is a main winding drum 102, having threaded grooves 103 throughout its length for the reception of a cable, and hub members 104 at its opposite ends. Journaled upon one of the hub members is 40 a gear wheel 105 that meshes with the pinion 98; the gear wheel being releasably secured to the drum 102 by bolts 106 received by openings in the web of the gear wheel, and in a flange 107 integral with the adjacent 45 end of the drum. The opposite end of the drum is provided with a web portion 108 that terminates in a widened friction rim 109. 110 represents a pinion journaled upon the other hub member at the opposite end 50 of the drum, and including a flange member 111, having transverse bolt receiving openings 112 therein that register with corresponding openings in the flange portion 108 of the drum, whereby the pinion may 55 be connected with the drum. The pinion 110 meshes with the gear wheel 95 and turns loosely upon the hub of the drum when the gear wheel 105 is secured to the opposite end of the drum. The pinion 39 60 and the gear wheel 95 are speed reducing gears between the gear 32 and the sleeve 97, and the pinion 98 and gear wheel 105 are speed reducing gears between the sleeve 97 and the drum 102 when the gear wheel 105 65 is secured to the drum; therefore, when the

gear wheel 105 is disengaged from the drum and the pinion 110 is secured thereto, the drum 102 will be driven at the same rate of speed as that of the drum 33 the gears 39 and 110 being of the same size. 70

113 represents a pinion journaled upon a stub shaft 114 carried by a bracket member 115 secured to a transverse frame member 116 and adjustably supported upon the vertical concentric flange 13¹ of the upper member 10 of the turntable by means of opposing set screws 117, as shown in Fig. 12. The bracket 115 also carries one end of a rock shaft 118, the opposite end of which is journaled in one of the bearing members 52 in 80 which the shaft 51 is journaled. Integral with the pinion 113 is a friction rim 119 that is adapted to engage with a friction wheel 120 carried by the opposite end of the rock shaft 118, and including a body member 121 85 that rotates freely between outside and inside circular plates 122 and 123, respectively; the plate 123 being prevented from rotating by means of a dowel pin 124 received by an opening in the plate and carried by the 90 bracket member 115; the opposite plate 122 being secured to the shaft 118 by means of the screw 125. The body member 121 is provided with an axial opening that receives a bushing 126, and 127 represents an eccentric 95 sleeve secured to the shaft 118 and operative to move the friction wheel bodily toward or from the friction rim 119, carried by the pinion 113 and the friction rim 109 of the drum 102. The pinion 113 meshes with the gear 100 32 and is given constant rotation.

128 represents a line guiding roller journaled upon the rock shaft 118, and 129 a supplemental line guiding roller journaled upon a vertically disposed stud 130 carried by a 105 bracket 131 secured to opposite sides of the transverse frame member 116 by means of the same bolts that secure the bracket member 115. The shaft 118 may be rocked in its bearings by means including a hand lever 110 132, having its lower end secured to a sleeve member 133 journaled upon the shaft 51 and provided with an inwardly extending arm 134 that is connected, by means of a link 135, with an arm 136 integral with a sleeve member 137 secured to the shaft 118, as by means of a set screw 138, the associated parts of the mechanism being so arranged that when the hand lever 132 is moved outward the friction wheel 120 engages with the friction rim 119 120 of the pinion 113 and the friction rim 109 of the drum 102 in a manner to rotate the drum in a reverse direction. 139 represents a horizontally disposed line guiding roller journaled upon a transverse shaft having its 125 opposite ends secured to the frame plates 15 below and in front of the drum 102, and 140 represents vertically disposed line guiding rollers that are journaled upon shafts 141 that are loosely received by any of a series of 130

openings 142 in upper and lower transverse frame members 143 and 144, respectively, whereby the rollers may be adjusted laterally as required.

5 The hoisting mechanism being mounted upon a turntable, it will turn freely in the direction of the line of pull, and when the angle of pull relative to the line of anchoring of the base member 1 reaches a degree sufficient to move the base member 1, it will swing around the anchorage from its initial position. When it is desired to lock the two parts of the turn-table together with the engine parallel with the base 1, as in moving 10 the machine, or at any desired angle, a locking pin 145 is provided that is loosely received by an opening in the upper member of the turn-table, and which may be received by any of a series of openings in the lower 15 member.

The first drum shaft 31, the main drum shaft 100, and the intermediate shaft 93 are secured in their respective bearing boxes, that are secured to the frame plates 15, being 20 received by gaps in the plates whereby the several shafts, with the various parts mounted thereon, may be readily removed when it is desired to transport the engine by team and wagon, as is usual in the districts 25 where it will be mostly used. The hand levers for controlling the movements of the various operative parts of the mechanism all move transversely of the machine and parallel with the axes of the shafts, the operator having the working parts of the engine 30 in full view at all times.

What I claim as my invention, and desire to secure by Letters Patent, is:

1. In a machine of the class described, in 40 combination, an engine frame including a turn table member longitudinally disposed, and parallel frame plates having their lower sides secured to opposite sides of said member, said plates having a series of gaps spaced 45 apart along their upper sides, said gaps having front and rear end walls, sleeved brackets received by said gaps and secured to said plates, and transverse gear carrying shafts having their opposite ends received by said 50 sleeved brackets and secured thereto, winding drums journaled upon said shafts, said sleeved brackets engaging with the end walls of said gaps in the direction of the line of pull of said drums and detachable laterally.

55 2. In a machine of the class described, a frame, an engine carried by said frame and including a power shaft, a hoisting mechanism carried by said frame including a series of fixed shafts, a winding drum carried 60 by one of said shafts, a gear wheel rotatable upon one of said fixed shafts and operatively connected with said power shaft, said wheel having a clutch rim, a combined clutch member and pinion rotatably and slidably mounted 65 upon said shaft, a sleeve journaled upon one

of said fixed shafts, a gear wheel secured to one end of said sleeve and engaging with said pinion, a pinion secured to the opposite end of said sleeve, a second winding drum rotatable upon one of said fixed shafts, a pinion 70 releasably secured to one end of said drum and engaging with the gear wheel secured to said sleeve, a gear wheel releasably secured to the opposite end of said drum and engaging with the pinion secured to said sleeve. 75

3. In a machine of the class described, a frame, an engine carried by said frame and including a power shaft, a hoisting mechanism carried by said frame including a series of fixed shafts, a gear wheel rotatable on 80 one of said fixed shafts and operatively connected with said power shaft, said wheel having a clutch rim, a winding drum carried by said shaft, a combined clutch member and pinion rotatably and slidably mounted 85 upon said shaft, a sleeve journaled upon one of said fixed shafts, a gear wheel secured to one end of said sleeve and engaging with said pinion, a supplemental rim forming part of said gear wheel and provided with 90 pawl engaging teeth, a pinion secured to the opposite end of said sleeve, a second winding drum rotatable upon one of said fixed shafts, a pinion releasably secured to one end of 95 said drum and engaging with the gear wheel secured to said sleeve, a gear wheel releasably secured to the opposite end of said drum and engaging with the pinion secured to said sleeve, and a locking pawl mechanism adapted to engage with said supplemental 100 rim in a manner to hold said second drum against a reverse rotation.

4. In a machine of the class described, a frame, an engine carried by said frame and including a power shaft, a hoisting mechanism carried by said frame including a series of fixed shafts, a gear wheel rotatable upon one of said fixed shafts and operatively connected with said power shaft, a winding drum mounted upon said fixed 105 shaft, said wheel having a clutch rim, a combined clutch member and pinion rotatably and slidably mounted upon said shaft, a sleeve journaled upon one of said fixed shafts, a gear wheel secured to one end of 110 said sleeve and engaging with said pinion, a pinion secured to the opposite end of said sleeve, a second winding drum rotatable upon one of said fixed shafts, a pinion releasably secured to one end of said drum and 115 engaging with the gear wheel secured to said sleeve, a gear wheel releasably secured to the opposite end of said drum and engaging with the pinion secured to said sleeve, said drum having a friction rim, and a motion reversing mechanism carried by said frame and adapted to engage with said friction rim. 120

5. In a machine of the class described, a frame, an engine carried by said frame and 125

including a power shaft, a hoisting mechanism carried by said frame including a series of fixed shafts, a gear wheel rotatable upon one of said fixed shafts and operatively connected with said power shaft, a winding drum mounted upon said fixed shaft, said wheel having a clutch rim, a combined clutch member and pinion rotatably and slidably mounted upon said shaft, a sleeve journaled upon one of said fixed shafts, a gear wheel secured to one end of said sleeve and engaging with said pinion, a pinion secured to the opposite end of said sleeve, a second winding drum rotatable upon one of said fixed shafts, a pinion releasably secured to one end of said drum and engaging with the gear wheel secured to said sleeve, a gear wheel releasably secured to the opposite end of said drum and engaging with the pinion secured to said sleeve, said drum having a friction rim, a rock shaft journaled in bearings carried by said frame, a friction wheel carried by said shaft, a fixed stud carried by said frame, a pinion journaled upon said stud and engaging with the first named gear wheel, a friction rim rotatable with said pinion; and means for moving said friction wheel toward or from the axes of said second drum and last named pinion whereby the direction of motion of said drum may be reversed.

6. In a machine of the class described, a frame, an engine carried by said frame and including a power shaft, a hoisting mechanism carried by said frame including a series of fixed shafts, a gear wheel rotatable upon

one of said fixed shafts and operatively connected with said power shaft, said wheel having a clutch rim, a winding drum mounted upon said fixed shaft, a combined clutch member and pinion rotatably and 40 slidably mounted upon said shaft, a sleeve journaled upon one of said fixed shafts, a gear wheel secured to one end of said sleeve and engaging with said pinion, a pinion secured to the opposite end of said sleeve, a 45 second winding drum rotatable upon one of said fixed shafts, a pinion releasably secured to one end of said drum and engaging with the gear wheel secured to said sleeve, a gear wheel releasably secured to the opposite end 50 of said drum and engaging with the pinion secured to said sleeve, said drum having a friction rim, a rock shaft journaled in bearings carried by said frame, a friction wheel carried by said shaft, a fixed stud carried 55 by said frame, a pinion journaled upon said stud and engaging with the first named gear wheel, a friction rim rotatable with said pinion, and means for moving said friction wheel toward or from the axes of said second 60 named drum and last named pinion whereby the direction of motion of said drum may be reversed, said means including an eccentric sleeve secured to said rock shaft, a bushing carried by said sleeve and having said friction wheel journaled thereon.
